ERIC C. MOORE, OF ROCHESTER, NEW YORK.

LOOSE-LEAF BINDER.

1,420,333.

Specification of Letters Patent. Patented June 20, 1922.

Application filed February 14, 1920. Serial No. 358,747.

To all whom it may concern:

Be it known that I, ERIC C. MOORE, of Rochester, in the county of Monroe and State of New York, have invented certain new and useful Improvements in Loose-Leaf Binders; and I do hereby declare the following to be a full, clear, and exact description of the same, reference being had to the accompanying drawings, forming a part of this specification, and to the reference numerals marked thereon.

My present invention relates to loose leaf or temporary binders for holding separate perforated sheets in book form by the provision of impaling posts upon one book cover cooperating with the other and occupying the perforations, and the invention has for its object to provide an improved construction whereby the capacity of the binder may be readily varied through the use of interchangeable impaling posts of different lengths in conjunction with an adjustable back adapted to be expanded and contracted to suit the length of the posts. To these and other ends the invention resides in certain improvements and combinations of parts all as will be hereinafter more fully described, the novel features being pointed out in the claims at the end of the specification.

30 In the drawings:

Figure 1 is a plan view of a binder constructed in accordance with and illustrating one embodiment of my invention, the same being in open position;

35 Figure 2 is an enlarged sectional view on the line 2—2 of Figure 1;

Figure 3 is an enlarged fragmentary sectional view on the line 3—3 of Figure 1 with the binder closed, and

40 Figure 4 is a view similar to Figure 3 but showing the binder expanded to increase its capacity.

Similar reference numerals throughout the several views indicate the same parts.

45 Referring first to Figures 1, 2 and 3, the major parts of the binder consist preferably of a pair of covers A and B connected by an intermediate two-part back C. The cover members include, in the present instance, connecting members 1 and 2 to which they are hinged at 3 and these cover members are in turn hinged at 4 to the back C. The hinges referred to may, as usual, consist of the leather or similar flexible covering used 55 to finish the binder as indicated at 5 in Figure 3.

One of the connecting members 1 is in the form of a channel and of sheet material forming a guide 6 open at one end to receive a bar 7 that may be slid longitudinally into the same or withdrawn therefrom. The bar carries a pair of impaling posts 8 rigidly fixed thereto as by riveting at 9 and these posts extend through the slot 10 in the top of the channel member. The operative position of the bar and posts is determined by an ear 11 struck up from the floor or the channel at one end, as shown in Figure 2, and which the end of the bar 7 abuts when it is fully inserted. The bar is then locked in position by a yielding spring latch formed by a tongue 12 also struck from the material of the bottom of the channel member 1 and having a projecting ear 13 engaging the outer end of the bar, as shown in Figure 2. The tongue may be depressed through the slot 10 to release the ear 13, but it engages automatically.

50 The other connecting member 2 is preferably in the form of an elongated sheet metal box provided as usual with apertures 14, as shown in Figure 1, to receive the ends of the impaling posts 8 when the binder is closed, as in Figure 3. The ends of the posts are notched at 15 forming a shoulder 16 that is engaged automatically by a sliding bolt 16 within the box-like connecting member 2 and operated by a spring 17 appearing in Figure 3. The engaging lip of the bolt shows in Figure 1 and it may be retracted 90 to release the impaling posts by operating a finger-piece 18 at one end. There is nothing new about this bolt 16 and hence it has not been illustrated in detail. When the two connecting pieces 1 and 2 are locked together in this manner by the impaling posts 8, they have a fixed relationship with each other and with the back C so that they confine between them the loose leaves on the impaling posts (not shown) and the covers 100 A B open and close on the hinges 3 instead of the hinges 4, the binder being fully extended as in Figure 1, with the covers turning on the hinges 4 only when it is desired to apply or remove the leaves or pages.

105 The purpose in making the impaling posts 8 and their carrying bar 7 removable is to permit them to be interchanged with other sets of impaling posts of greater or less length to produce a binder of correspondingly greater or less capacity. Impaling posts of greater length than those shown in

Figures 1, 2 and 3 are shown in place and indicated at 8^a in Figure 4, being mounted upon a bar 7^a. When these larger impaling posts are applied, the back C must also be enlarged or extended for which purpose the two-part construction, mentioned, is used. One part 19 is provided with a plurality of transverse slots 20 in which are slidable a plurality of bolts 21 secured in the other part 22 and tightened by nuts 23 to hold the two parts of the back in different expanded or contracted positions of relative adjustment. Through the use of this means, the back is shown as of minimum width in Figure 3 and of maximum width in Figure 4. Preferably the two back pieces are cut away in a complementary manner, as shown, so that their outer faces will be in the same plane and lie flush against the contacting surface.

A binder constructed in accordance with my invention is strong and convenient to use while possessing sufficient elasticity in the matter of capacity to properly accommodate widely different quantities of leaves.

I claim as my invention:

1. In a loose leaf binder, the combination with a pair of covers, of a two-part back rigidly connecting them in hinged relationship, the parts of said back being adjustable one upon the other to change the degree of separation of the two covers, and two detachable interchangeable sets of impaling posts of different length each adapted to be carried by one cover and to cooperate with the other.

2. In a loose leaf binder, the combination with a pair of covers, of a two-part back rigidly connecting them in hinged relationship, one of said parts being slotted and the other being provided with a fastener cooperating with the slot to maintain the slotted part in different adjusted positions affecting the degree of separation of the covers, and two detachable interchangeable

sets of impaling posts of different lengths each adapted to be carried by one cover and to cooperate with the other.

3. In a loose leaf binder, the combination with a pair of covers, of a two-part back rigidly connecting them in hinged relationship, the parts of said back being adjustable one upon the other to change the degree of separation of the covers, and a bar slidably interlocked with one cover and carrying impaling posts cooperating with the other cover.

4. In a loose leaf binder, the combination with a pair of covers, of a two-part back rigidly connecting them in hinged relationship, the parts of said back being adjustable one upon the other to change the degree of separation of the covers, a bar slidably interlocked with one cover and carrying impaling posts cooperating with the other cover, and a latch for releasably locking the bar in position.

5. In a loose leaf binder, the combination with a back and a pair of covers hinged thereto, one of said covers embodying a channel member having a guideway parallel to the axis of the hinge, of a bar adapted to be inserted in and removed from the guideway and held thereby interlocked with the channel member, and impaling posts carried by the bar and cooperating with the other cover member.

6. In a loose leaf binder, the combination with a back and a pair of covers hinged thereto, one of said covers embodying a channel member having a guideway parallel to the axis of the hinge, and having a tongue struck out from a wall thereof to provide a longitudinally extending spring latch, of a bar adapted to be inserted longitudinally in and removed from the guideway and to be retained therein by the latch, and impaling posts carried by the bar and cooperating with the other cover member.

ERIC C. MOORE.
